UNITED STATES PATENT OFFICE.

ROBERT M. RILEY, OF NEW YORK, N. Y., AND JOSEPH E. FISHER, OF MILLVILLE, OHIO.

DESIGN FOR A GAME-BOARD.

SPECIFICATION forming part of Design No. 29,196, dated August 9, 1898.

Application filed July 1, 1898. Serial No. 684,984. Term of patent 3½ years.

To all whom it may concern:

Be it known that we, ROBERT M. RILEY, a resident of the city of New York, in the State of New York, and JOSEPH E. FISHER, a resident of Millville, in the county of Butler and State of Ohio, both citizens of the United States, have invented and produced a new and original Design for a Game-Board, of which the following is a specification, reference being had to the accompanying drawings, forming part thereof.

Figure I is a plan view of a game-board, showing our new design. Fig. II is a sectional view taken on line II II, Fig. I.

As shown in the drawings, the leading or material feature of our design consists of a base 1, from the periphery of which rises a wall 2.

On the base within the wall is a raised portion or body 3, having an irregular outline, and on one side thereof an opening or space 4, with a contracted neck 5, located between two arms 6 and 7 of the body 3. Near the arm 6, but separated therefrom by a space 8, is a raised portion 9, and near the arm 7, but separated therefrom by a space 10, is a raised portion 11.

We claim as our invention—

The design for a game-board substantially as herein shown and described.

ROBERT M. RILEY.
JOS. E. FISHER.

In presence of—

E. S. KNIGHT,
STANLEY STONER.
